DESIGN FOR A BLANK FOR A PENDANT CRUCIFORM

Meyer Reiff, Philadelphia, Pa.

Application April 19, 1939, Serial No. 84,383

Term of patent 7 years

To all whom it may concern:

Be it known that I, Meyer Reiff, a citizen of the United States, residing at Philadelphia, in the county of Philadelphia and State of Pennsylvania, have invented a new, original, and ornamental Design for a Blank for a Pendant Cruciform, of which the following is a specification, reference being had to the accompanying drawing, forming a part thereof.

In the drawing, Fig. 1 is a plan view and Fig. 2 is an edge view of a blank for a pendant cruciform showing my new design.

I claim:

The ornamental design for a blank for a pendant cruciform, as shown.

MEYER REIFF.
